UNITED STATES PATENT OFFICE.

MATTHIAS BROCK, OF BOSTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

LASTING-MACHINE.

1,341,732.

Specification of Letters Patent.

Patented June 1, 1920.

Application filed November 22, 1916. Serial No. 132,892.

To all whom it may concern:

Be it known that I, MATTHIAS BROCK, a citizen of the United States, residing at Boston, in the county of Suffolk and State of Massachusetts, have invented certain Improvements in Lasting-Machines, of which the following description, in connection with the accompanying drawings, is a specification, like reference characters on the drawings indicating like parts in the several figures.

This invention relates to lasting machines and is herein shown as applied to a machine of the type shown in prior United States Letters Patent No. 1,066,375, granted July 1, 1913, upon my application.

In the use of a machine of the type shown, a shoe is applied to a heel spindle while the spindle occupies a depressed and advanced position with relation to a heel band and heel seat wipers relatively to which it is subsequently jacked backwardly and upwardly into operative position by mechanism which includes a hand wheel for drawing the shoe back and a foot treadle for raising the shoe. In the machine shown in said patent the foot treadle and hand wheel are locked by separate pawls to maintain the jacking pressures at the heel. The machine is also equipped with toe jacking mechanism, including a foot operated treadle one depression of which effects jacking up of the toe of the shoe and the next alternate depression of which effects the unjacking of the toe.

In accordance with a time and labor saving feature of the invention covered by that patent, the unjacking of the heel is caused to follow automatically the unjacking of the toe. It is an object of this invention to improve the machine of United States Letters Patent No. 1,066,375 in respect to this feature. In the machine the pawl that locks the foot treadle controlling the heel pressure was operatively connected with the toe jacking foot treadle, as shown in Fig. 13 of the patent drawings, so that the pawl was lifted by every depression of the toe jacking treadle. Therefore the operator could not jack up the heel until after he had jacked up the toe, because the toe jacking would release the heel jacking treadle. The shoe must, however, be jacked back into the heel band before the toe jack-

ing is effected, as is well understood. I have found that there is a substantial advantage 55 in jacking the heel up to approximately its full elevation relatively to the wipers before it is jacked back into the band, because if the jacking up follows the jacking back it tends to force the last up too much within 60 the shoe upper materials, disarranging the latter. In prior United States Letters Patent, No. 1,018,477, granted February 27, 1912, upon my application, a treadle is provided for raising the heel post which is independent of the toe post elevating mechanism, the machine, however, not being provided with mechanism for automatically lowering the heel post concurrently with the lowering of the toe post as in prior United 70 States Letters Patent No. 1,066,375. It is an object of my invention to provide a lasting mechanism which will have the advantage of the labor-saving feature of prior United States Letters Patent No. 1,066,375 75 with the additional advantage of a construction permitting operation in the desired sequence. I have by the present invention provided an organization in which the most advantageous sequence of operations known 80 to me can be followed and the objections to the earlier machine eliminated. This invention is embodied in a novel construction and arrangement of mechanism which will now be described, and the several 85 features of the invention will then be pointed out in the claims.

Figure 1 of the drawings is a side elevation of a lasting machine equipped with the present improvements.

Fig. 2 shows in end elevation a portion of the means with which machines of the illustrative type are provided for raising and lowering the toe post.

Fig. 3 shows in front elevation and partly 95 in vertical section a portion of the mechanism of Fig. 2 together with the means with which machines of this type are provided for releasing the heel lasting carriage.

Fig. 4 is a perspective view illustrating novel portions of the mechanism of this invention.

The machine which in general resembles closely the machine fully described in prior 105 Patent No. 1,066,375, comprises a frame A

upon the right hand end of which a heel lasting mechanism B, including a movable heel lasting carriage, occupies a constant operative position in which it is held by a latch 144 and from which it is moved rearwardly to permit insertion and removal of the work. The heel lasting mechanism comprises a heel band 2 and heel seat wipers 3. The frame A also supports a toe lasting mechanism C which is adjustable thereon toward and from the heel lasting mechanism to adapt the machine for operating upon shoes of different lengths. The shoe is supported for the lasting operation by a heel post carrying a last spindle 5, and by a toe post carrying a toe rest 6 and which is arranged to be elevated by the mechanism disclosed in said prior United States Letters Patent No. 1,066,375 and controlled by foot treadle 176 for jacking up the toe of the shoe, and to be returned to lowered position in response to a second actuation of treadle 176 for unjacking the shoe to permit it to be removed from the machine. This mechanism as shown in Figs. 2 and 3 comprises a cam shaft 9 to which is fixed a ratchet wheel 10 engaged by a pawl 11 mounted on a pawl carrier 12 which is supported loosely for turning movement on the cam shaft 9 and connected by a rod 13 with the treadle 176. The shaft 9 carries a cam wheel 14 having alternate elevations and depressions and arranged to engage a roll 17 on a vertically movable slide 18 which is guided in the frame of the machine and is constructed to provide a support for the toe post by engagement with an adjustable screw 19 at the lower end of the post. In the operation of this mechanism one depression of the treadle 176 will serve to turn the ratchet wheel 10 a sufficient distance to move one of the elevations of the cam wheel 14 beneath the roll 17 and thereby elevate the toe post, which will remain in elevated position until the next succeeding depression of the treadle 176 whereby the cam shaft will be turned a sufficient distance to remove the elevated portion of the cam wheel from beneath the roll 17 and permit the toe post to return to its lowered position.

The heel post is vertically movable in a horizontally movable slide 8 which has operative connection with a hand wheel 148 by means of which the heel post is jacked back into the heel band after a shoe has been applied to the last spindle. The extent to which the heel post, with the shoe thereon, can be jacked back into the band depends upon the size of the shoe or the last and the position of the spindle hole in the last with relation to the rear end face of the last. There is therefore provided, as fully explained in said Patent 1,066,375, a friction pawl 150 for locking the hand wheel, together with mechanism fully described in

said patent, for automatically unlocking the hand wheel when the shoe is to be unjacked.

The heel spindle rests down, by an adjustable screw bolt 15, as shown in Fig. 4, upon the vertically swinging plate 16 the rear end 70 of which is pivoted to the slide 8 and the front end of which in turn rests upon an elevating rod 210 operatively connected at its lower end with a foot treadle 212 having a ratchet face adapted to be engaged by a 75 locking pawl 214 pivoted at 215 and having a foot piece 218 by which the pawl can be lifted independently of the movement of any other part of the machine. Under normal conditions, however, it is desirable to 80 save an operator the time and effort of manipulating the pawl 214 to unlock the elevating rod. In accordance with this invention this result is obtained by mechanism that is unaffected by that depression of the 85 toe rest treadle 176 which is employed for jacking up the toe of the shoe, as will be hereinafter explained. This organization makes it possible for the operator, after having applied a shoe to the heel spindle 5, 90 to elevate the heel post to bring the shoe approximately into the plane of the heel seat wipers 3 and thereafter, while the pawl 214 holds the shoe elevated, to jack the shoe back into the heel band by means of the 95 hand wheel 148 and then to jack up the toe of the shoe by means of the treadle 176. This is the most advantageous sequence of steps now known to me because it provides for jacking the shoe into the heel band at the 100 correct elevation and avoids displacing the last upwardly in the shoe after the shoe has been embraced by the heel band.

As explained in said prior patents, the latch 144 that locks the heel carriage is 105 automatically released in response to the unjacking depression of the foot treadle 176, allowing retracting spring 145 to slide the heel carriage rearwardly, and in the continued depression of treadle 176 the operator 110 depresses a treadle 165 for effecting release of the locking pawl 150 from hand wheel 148. The mechanism for releasing the heel carriage is shown in detail in Fig. 3 and comprises a rock shaft 81 upon which the 115 latch 144 is mounted, and an arm 83 carried by the rock shaft 81 and extending over a cross bar 84 supported upon a vertically movable rod 87 operated by a cam 89 upon the cam shaft 9. In the operation of this mechanism, that movement of the treadle 176 whereby the toe post is released and permitted to return to its lowered position serves to operate the cam 89 in such a manner as to raise the arm 83 and thereby 120 elevate the latch 144 for releasing the heel carriage, thus permitting the heel carriage to be moved rearwardly through the action of its spring 145.

In accordance with the illustrative em- 130

bodiment of this invention the heel lasting carriage has a laterally projecting stud 25 arranged to engage, during the rearward movement of the heel lasting carriage, with the upright arm 26 of a rockshaft 27 having a horizontal arm from which is suspended a lifting plate 28. The lifting plate underlies the head of a lifting rod 30 operatively connected with the pawl 214 so that when the heel carriage moves rearwardly, or toward the right in Fig. 1, the shaft 27 will be rocked, lifting plate 28 and the pawl-lifting rod 30. This arrangement provides that the elevating rod 210 will be released and allow the heel post and the shoe to drop away from the heel wipers automatically and concurrently with the other unjacking operations. The arm 26 has a depressible end member 40 provided with a rearwardly and downwardly inclined face to engage the stud 25 and cause the stud to force the member out of its way as the heel lasting carriage is moved toward the left to its working position.

Having explained the nature of this invention and described an illustrative embodiment thereof, I claim as new and desire to secure by Letters Patent of the United States:—

1. A lasting machine having, in combination, a toe post, a treadle and connected mechanism to alternately raise the post and lower the post on successive actuations of the treadle, a heel post, an elevating treadle for the heel post, a locking pawl for said last named treadle arranged to hold the heel post elevated during the operation of raising the toe post, and means for automatically releasing the locking pawl upon the lowering of the toe post.

2. In a lasting machine, a movable heel lasting carriage, heel post elevating mechanism operative independently of said heel carriage and including a locking pawl, heel lasting carriage latching means, heel carriage retracting means automatically acting when the latching means is released, and means arranged to operate automatically during retraction of the carriage to release said locking pawl.

3. A lasting machine having, in combination, a forwardly and backwardly movable heel lasting carriage, a heel post, mechanism operative independently of said carriage for elevating the heel post and holding it upraised, and means arranged to be operated by said carriage during its backward movement to release the heel post elevating and holding mechanism.

4. A lasting machine of the class described having, in combination, a forwardly and rearwardly movable heel lasting carriage, heel post elevating means, a locking pawl for said means operative to lock the post raised independently of said carriage,

and connections becoming operative during the rearward movement of the carriage for automatically releasing said pawl.

5. A lasting machine of the class described having, in combination, a forwardly and rearwardly movable heel lasting carriage, a heel post elevating means operative independently of said carriage, a locking pawl therefor, manually operative means for releasing the pawl, and means operating automatically during the rearward movement of the carriage to release the locking pawl.

6. A lasting machine having, in combination, a toe post, a treadle and connected mechanism alternately to raise the post and to depress the post on successive actuations of the treadle, a movable heel lasting carriage, latching means therefor, retracting means for the carriage automatically operative when said latching means is released, a heel post, mechanism operative independently of said carriage for elevating the heel post and holding it upraised during the operation of raising the toe post, means for releasing the heel carriage latching means concurrently with the lowering of the toe post, and means operative upon the lowering of the toe post for automatically releasing the holding means for the upraised heel post.

7. A lasting machine having, in combination, a forwardly and rearwardly movable heel lasting carriage, latching means therefor, a toe post, a treadle and connected mechanism organized alternately to raise the toe post and to depress the toe post and concurrently release said carriage latch on successive actuations of the treadle, retracting means for said carriage automatically operative when the latching means is released, a heel post, mechanism for elevating the heel post and latching it upraised independently of the movement of said carriage, and means arranged to be operated by the released carriage during its backward movement to release the heel post latching means.

8. A lasting machine having, in combination, a toe post, a heel lasting carriage movable toward and from said toe post, latching means to lock the carriage moved toward said toe post, a treadle and connected mechanism alternately to raise the post and to depress the post and release the carriage on successive actuations of the treadle, a heel post, means for elevating and locking the heel post upraised independently of the toe post and lasting carriage, and means for automatically releasing the heel post locking means in consequence of the lowering of the toe post and the release of the carriage.

9. In a lasting machine of the class described, in combination, a toe post, a treadle and connected mechanism to raise the post and lower the post on successive actuations

of the treadle, a heel post, a treadle and connected means for raising the heel post, means for locking the heel post in raised position, and means unaffected by the raising of the toe post and operative independently of the toe post treadle mechanism for releasing the heel post locking means.

10. In a lasting machine of the class described, in combination, a movable heel lasting carriage, means for latching the carriage in operative position and for automatically retracting the carriage when released, a toe post, a treadle and connected mechanism for raising the toe post on one actuation of the treadle and for lowering the toe post and releasing the heel carriage latch on the next succeeding actuation of said treadle, a heel post, means to raise the heel post and to latch it in raised position independently of the heel carriage, and means arranged automatically to operate during retraction of said carriage to release the heel post latching means.

11. In a machine of the class described, a toe post, means for alternately raising and lowering said toe post, a heel post, means for raising said heel post, means unaffected by the raising of the toe post for locking the heel post in upraised position, and means automatically operative upon the lowering of the toe post to cause said locking means to release the heel post.

12. In a machine of the class described, a toe post, means for alternately raising and lowering said toe post, a heel post, means for raising said heel post, a locking device for retaining the heel post in upraised position during the raising of the toe post, and means connected to said locking device and automatically operative upon the lowering of the toe post to cause said device to release the heel post.

In testimony whereof I have signed my name to this specification.

MATTHIAS BROCK.
